CLAIM

The ornamental design for a food container lid, as shown and described.

DESCRIPTION

FIG. 1 is a top front right isometric view of a food container lid showing the new design; FIG. 2 is a bottom rear left isometric view thereof; FIG. 3 is a front view thereof; FIG. 4 is a rear view thereof; FIG. 5 is a left side view thereof; FIG. 6 is a right side view thereof; FIG. 7 is a bottom view thereof; and FIG. 8 is a top view thereof; and, FIG. 9 is a top front right isometric view thereof, shown with the top layer of the food container lid partially peeled away from the lower layer, and further shown in an environment of use with an exemplary food container body. The broken lines are shown for purposes of illustrating an exemplary food container body and form no part of the claimed design.
